C. O. GUERNSEY

REMOTE CONTROL APPARATUS

Filed Nov. 18, 1924

Inventor

Charles O. Guernsey
by his Attorneys:-
Hoover & Hoover

UNITED STATES PATENT OFFICE.

CHARLES O. GUERNSEY, OF PHILADELPHIA, PENNSYLVANIA.

REMOTE CONTROL APPARATUS.

Application filed November 18, 1924. Serial No. 750,704.

The object of this invention is to provide means for controlling the spark, or throttle, of an internal combustion engine from the remote point, such as the cab of an omnibus, or other vehicle.

It will be understood that the invention, while especially adapted for use in connection with the motor power of an omnibus, can be used on railroad cars, ships, or other 10 places for the handling of the spark advance, or the throttle opening, oil pressure mechanism, or for engaging or disengaging the clutch, or for shifting or neutralizing gearing.

15 In the accompanying drawing:

Fig. 1 is a diagrammatic side view illustrating my remote control apparatus.

Fig. 2 is an enlarged vertical sectional view showing in detail a type of valve which 20 may be used.

The variable pressure reducing valve 1 may be of an ordinary type. In order that the invention may be clearly understood I have shown in Fig. 2 one form of reducing 25 valve which is found satisfactory, but it will be understood that this reducing valve is well known in the art and does not of itself constitute any part of my invention. The valve 1 is connected with a pipe 2 which 30 supplies air under pressure from any suitable source. The valve is provided with a main chamber 2^a and a valve 2^b is interposed between the pipe 2 and the chamber. A valve 2^c is interposed between the chamber 35 and a suitable exhaust port 2^d. The upper part of the chamber 2^a is closed by a diaphragm 2^e to the top of which pressure is applied by means of a spring 2^f. By means of a handle 3 which cooperates with cam 40 surfaces 3^a the spring 2^f can be adjusted to vary the pressure applied to the top of the diaphragm 2^e. A discharge pipe 4 communicates with the chamber 2^a at 4^a.

When pressure is admitted to the valve 45 through the pipe 2, the diaphragm 2^e is forced upward in opposition to the spring 2^f thus closing or partly closing the valve 2^b and increasing the opening of the valve 2^c. The closing of the valve 2^b and the 50 opening of the valve 2^c causes a definite pressure to be established in the chamber 2^a, this pressure being determined by the pressure exerted by the spring 2^f. Any change in the pressure in the chamber 2^a consists

in corresponding changes in the positions of 55 the valves 2^b and 2^c, and in this way the pressure in the chamber is maintained constant. The pipe 4 leads to the pressure end of a cylinder 5, in which is a piston 6. The piston rod 7 of the piston is connected by a 60 link 8 to one arm 9 of a lever 10, which is pivoted at 11 to any fixed point. Attached to the other arm 12 of the lever is a coiled spring 13, which, in turn, is secured to a 65 fixed bracket 14. This spring opposes the pressure of air in the cylinder 5. The valve 1 is such that any desired pressure from zero to the maximum in the supply pipe can be maintained in the pressure end of the cylinder 5.

70 The pressure in the cylinder is opposed by the spring 13 so that, by varying the amount of pressure admitted to the cylinder, it is possible to hold the piston at rest at any desired point of the stroke. The piston 75 through its rod and link 8 can be connected to a suitable spark or throttle advance, or throttle mechanism of an internal combustion engine of an omnibus, or other vehicle. It can also be used for other purposes where 80 it is desired to shift the mechanism and to hold it at a predetermined point.

I claim:

1. The combination in a remote control apparatus, of a pipe for supplying air under 85 pressure; a pressure reducing valve connected to said pipe, the said valve being adjustable to maintain any desired pressure; an air cylinder connected to the valve; a piston in the cylinder; and a spring for balancing 90 the pressure within the cylinder to hold the piston in the position in which it is adjusted.

2. The combination in a remote control apparatus, of a pipe for supplying air under 95 pressure; a pressure reducing valve connected to said pipe, the said valve being adjustable to maintain any desired pressure; an air pressure cylinder connected to the valve; a piston in the cylinder, said piston having a rod; a pivoted lever, one arm of said lever 100 being connected to the piston rod; and a balancing spring connected to the other arm of the lever and to a fixed point, said piston being adapted to be connected to a spark advance, throttle, or other device, so as to 105 be held in the position in which it is adjusted.

CHARLES O. GUERNSEY.
